United States Patent Office

Des. 209,394
Patented Nov. 28, 1967

209,394

INSECT BAIT HOLDER

Heiko T. de Man, Moraga, Calif., assignor to
Alan C. Richardson, Nevada City, Calif.

Filed Jan. 20, 1967, Ser. No. 5,508

Term of patent 14 years

(Cl. D22—19)

FIG. 1 is an elevation of an insect bait holder showing my new design;

FIG. 2 is a top plan view thereof;

FIG. 3 is an elevation thereof, with portions partially shown in cross-section.

I claim:

The ornamental design for an insect bait holder, as shown.
